WITNESS:

UNITED STATES PATENT OFFICE.

JOSEPH HENRY BANKS, OF NORTH ANDOVER, MASSACHUSETTS.

CHAIN HOLDER.

Application filed April 1, 1922. Serial No. 548,835.

To all whom it may concern:

Be it known that I, JOSEPH H. BANKS, a citizen of the United States, residing at North Andover, in the county of Essex and State of Massachusetts, have invented new and useful Improvements in Chain Holders, of which the following is a specification.

My present invention has reference to a watch chain holder for belts.

10 In the ordinary construction of belts no provision is made for sustaining the bar of a watch chain thereon, and as watches are extensively worn in the watch pocket of men's trousers a serious liability of loss of 15 the watch is thus afforded.

It is therefore the principal object of the present invention to produce an extremely simple, cheap, ornamental and effective attachment for belts whereby the bar of a

20 watch chain may be effectively clamped thereon and as readily removed when desired.

It is a further object to produce a device of this character in the nature of a plate 25 bent upon itself to form a substantially rectangular yoke through which the belt is passed, said yoke having impinging means to enter the belt to hold the yoke on the belt, said yoke having its outer face provided with a central opening and having 30 clamping fingers on the sides of the openings, said fingers designed to receive therebetween the bar of the watch chain to sustain the ring or enlargement on the bar in 35 the opening of the yoke to effectively prevent the accidental removal of the bar from the holder.

The foregoing objects may be accomplished by a construction, combination and 40 operative association of parts such as are disclosed by the drawings which accompany and form part of this specification.

In the drawings:—

Figure 1 is a perspective view illustrating 45 the application of the improvement.

Figure 2 is a greatly enlarged approximately central transverse sectional view through the improvement and belt.

The body of the improvement is in the 50 nature of a metal plate bent or folded upon itself to provide a substantially rectangular yoke member both indicated by the numeral 2. The yoke has its inner face indented to provide impinging elements 3 which enter 55 the belt to hold the yoke against movement thereon. The outer face of the yoke is cen-

trally provided with an opening 4, and on the said outer face on the opposite sides of the opening are spring clamping fingers 5 respectively; from their juncture with the yoke 60 the fingers are arched but have their ends in contacting engagement with the outer face of the yoke, the free extremities of the said fingers being rounded outwardly. By such construction it will be noted that the bar 6 of a watch chain 7 may be readily inserted 65 between the yoke and the spring clamping fingers, and the ring or central enlargement 8 on the bar, to which the chain is directly connected, is received in the opening 4 of the 70 yoke. The result is that the bar cannot be accidentally removed from the holder, but an outward pull on the bar will readily remove the same when it is desired to disassociate the chain from the belt. 75

What I claim is:—

1. The combination with a belt, of a means for holding the bar of a watch chain thereon, comprising a plate secured to the belt and provided with a central opening, said 80 plate having spring fingers on the opposite sides of the opening to clamp therebetween the bar of the chain and to hold the chain attaching ring on the center of the bar in the opening. 85

2. The combination with a belt, of a means for clamping the bar of a chain thereto, comprising a plate secured on the belt having its outer face provided with downwardly directed outwardly arched spring fingers 90 whose ends are in contact with the plate and the extremities of the said ends rounded outwardly, said plate being provided with an opening disposed centrally between the fingers whereby to receive the attaching ring 95 of the chain bar therein when the bar is arranged between the fingers and clamped thereby against the plate.

3. The combination with a belt, of a means for clamping the bar of a watch chain thereto, comprising a plate shaped to provide a substantially rectangular yoke that receives the belt therethrough, impinging means on the yoke entering the belt, said yoke having its outer face, adjacent its edges provided with spring fingers and having an opening 100 between the fingers to receive the ring that attaches the chain to the bar when the bar is arranged between the fingers and clamped thereby against the yoke. 105

In testimony whereof I affix my signature.

JOSEPH HENRY BANKS.
